DESIGN FOR A BROOCH OR SIMILAR
ARTICLE

Lester L. Hess, New York, N. Y.

Application November 30, 1948, Serial No. 149,880

Term of patent 3½ years

(Cl. D45—19)

To all whom it may concern:

Be it known that I, Lester L. Hess, a citizen of the United States, residing at 1120 Park Avenue, New York city, in the county of New York and State of New York, have invented a new, original, and ornamental Design for a Brooch or Similar Article, of which the following is a specification, reference being had to the accompanying drawing, constituting a part thereof.

Fig. 1 is a top plan view of a brooch or similar article showing my new design.

Fig. 2 is a front elevational view.

Fig. 3 is a side elevational view.

I claim:

The ornamental design for a brooch or similar article, substantially as shown.

LESTER L. HESS.
